UNITED STATES PATENT OFFICE

CORA BRAITHWAITE BATTIN, OF NEW YORK, N. Y., ASSIGNEE TO G. FOREST BRAITHWAITE, OF WOOD-RIDGE, NEW JERSEY

GARMENT SUPPORTER

Application filed December 30, 1930. Serial No. 505,476.

This invention relates to garment supporters, and more particularly it pertains to a new and novel means for attaching garment supporters such as garters and the like to garments.

I have illustrated a very similar device in a co-pending application filed by me August 24, 1929, Serial Number 388,157, and the device of the present application is considered 10 an improvement over the device illustrated in said application above mentioned.

It is one of the objects of the present invention to provide a pin fastener which may be readily attached and removed with respect 15 to a garment such for example as a corset.

It is another object of the invention to provide a device of the afore-mentioned character which will not be bulky and which will accordingly be comfortable to the wearer and 20 which will present an extremely neat and attractive appearance.

Still another object of the invention resides in a novel construction whereby none of the metallic parts come in direct contact with 25 the person of the wearer.

Still a further object of the invention resides in a novel construction which will be both cheap and easy of manufacture.

With the above and other objects in view, 30 reference is to be had to the accompanying drawing forming part of this application, in which;

Figure 1 is a view in front elevation showing 35 a garter attached to a garment such as the lower edge of a corset by a device constructed in accordance with the present invention,

Figure 2 is a fragmentary longitudinal 40 sectional view thereof,

Figure 3 is a view in front elevation illustrating a device constructed in accordance with one form of the present invention,

Figure 4 is a view in rear elevation illustrating a slightly modified form of device,

Figure 5 is a detail sectional view of the form of the invention illustrated in Figure 4,

Figure 6 is a view in elevation illustrating a still further modified form of the invention,

Figure 7 is a detail sectional view of that form of the invention illustrated in Figure 6,

Figure 8 is a detail sectional view of a slightly modified form of the invention;

Figure 9 is a perspective view illustrating that form of the invention shown in Figure 4, together with the pin employed in combination with the device of this invention.

Referring more particularly to the drawing, and particularly to Figures 1 to 3 inclusive, the reference numeral 10 designates the lower edge of a garment such for example as a corset. The reference numeral 11 designates a garter which carries a conventional type of clasp such as 12, and said garter is attached to the lower edge of the corset or other garment by a device constructed in accordance with the present invention.

In accordance with the present invention it is contemplated to attach the garter 11 to the garment 10 by means of a pin fastener such as 14. This pin fastener 14 is adapted to pierce the garment 10, and the pin member 15 thereof is adapted for engagement with a suitable device carried by the garter, in a manner to be hereinafter described.

In accordance with that form of the invention illustrated in Figures 2 and 3, the device carried by the garment consists of a main body portion 20 having a plurality of pin receiving loops 21 projecting from one edge thereof. The main body portion of this member is provided with a slot 22 through which the garter 11 may be looped as at 23 and secured by a suitable line of stitching such as 24. This construction presents a plurality of pin receiving loops which are adapted to receive the pin member 15 of the pin to attach the garter to the garment 10. In

accordance with the invention, a suitable piece of tape or other material designated 25 may be secured to the garter 11 in order to protect the person of the wearer from contact with the metal parts thereof and this piece of tape 25 is preferably secured by the line of stitching 24 heretofore mentioned.

The member 20 is formed by cutting a rectangular piece of metal in such manner that 10 the loops 21 and the slot 22 will be formed when the metal is bent upon itself upon a medial line, and it will be noted that the pin receiving loops 21 are preferably spaced with relation to each other, and also with relation to the ends of the body portion 20.

In that form of the invention illustrated in Figures 4 and 5, the member 20 is formed with pin receiving loops 21 which are provided by suitably cutting the blank from

20 which the device is formed as heretofore described. In this last mentioned form of the invention, however, attaching means in the form of prongs 30 are provided, and these prongs 30 are formed by so cutting the blank 25 of material that when it is bent upon itself along a medial line to form the pin receiving loops 21, the prongs 30 will extend from one edge of the body portion of the device in alignment or substantial alignment with the pin receiving loops 21. In attaching this 30 form of the invention to the garter 11, the end of the elastic forming the garter is positioned against the body portion 20 of the device, and the prongs 30 are bent over to the 35 rear through the fabric of the garter 11 as best illustrated at 31 in said Figure 5. By this means it will be apparent that the device may be attached to the garter 11 without sewing or stitching of any type.

40 In Figure 6, the device is illustrated as provided with a plurality of openings 33 arranged in a longitudinally extending series which extends from and to the end of the body portion of the device and in this form 45 of the invention the garter 11 is secured to the body portion 20 by means of hollow rivets or eyelets or similar means designated 34 in Figures 6 and 7.

In Figure 8, the device is illustrated as 50 similar to that form illustrated in Figures 6 and 7. In this last mentioned form of the invention, however, the body portion 20 is secured to the garter 11 by means of stitching or the like 35 which passes through the openings 34 in the body portion 20.

55 In Figure 9, the device is shown as comprising a main body portion 40 having a slot 41 extending longitudinally thereof. This body portion 40 is formed from a suitable 60 blank of material which is cut out so that when it is bent upon itself along a medial line, the body portion will comprise two complementary members. One of the members is provided with a plurality of projecting 65 tongues 42 and in bending the device upon

the medial line, pin receiving loops 43 are formed which loops are spaced with respect to each other and also with respect to the ends of the body portion 40 and it will be noted that the tongues 42 are positioned between the pin receiving loops 43 and also between the loops and the ends of the body portion 40. In this form of the invention, a plurality of openings 45 are formed in the main body portion 40 and extend from end to end 75 thereof at a point between the pin receiving loops and the slot 41.

In use, a pin member such as 14 heretofore described is employed, and this pin member is inserted first through the garment 10 and then through the pin receiving loops of the attaching device after which the pin member is again passed through the garment and has its free end engaged behind a keeper 15.

Thus it will be seen that the present invention provides a new and novel device for attaching garters and similar garment supporters to a garment, which device may be readily manipulated, presents a neat and pleasing appearance, is not bulky in form, and is also of a cheap and easy manufacture.

While the invention has been herein disclosed in its preferred forms, it is to be understood that the invention is not to be limited to the constructions herein illustrated, but may be practiced in other forms which rightfully fall within the scope of the appended claims.

Having thus described the invention, what is claimed as new, and what it is desired to secure by Letters-Patent of the United States, is;

1. A pin attaching device for garters and similar devices comprising a body portion, a plurality of pin receiving loops projecting from one edge of said body portion, and a plurality of integral tongues between each end of said body portion and said pin receiving loops and adapted to be bent backwardly upon the body portion for securing the device to a garter.

2. A pin attaching device for garters and similar devices, comprising a blank bent upon itself to provide a body portion, a plurality of pin receiving loops projecting from one edge thereof, a slot formed in said body portion adjacent that edge opposite to the edge upon which said pin receiving loops are formed, and a plurality of relatively small openings extending longitudinally of the body portion and arranged between said slot and said pin receiving loops.

3. A pin attaching device for garters and similar devices comprising a blank of metal bent upon itself to provide a plurality of pin receiving loops projecting from one edge thereof, and a plurality of prongs projecting from said body portion adjacent said pin receiving loops and adapted to be bent upon the body portion to attach said device to a garter.

4. A pin attaching device comprising a rec-

tangular blank so cut as to provide a plurality of pin receiving loops and attaching prongs adjacent said pin receiving loops when the blank is bent upon itself along a medial line.

5. A pin attaching device comprising a main body portion, a plurality of spaced pin receiving loops projecting from one edge of said main body portion, said pin receiving loops being also spaced from the ends of the body portion, and attaching prongs formed integral with said body portion and arranged between the pin receiving loops, and between the pin receiving loops and the ends of the main body portion.

15 In testimony whereof I affix my signature.
CORA BRAITHWAITE BATTIN.
